(57) **CLAIM**

The ornamental design for a food chopper, as shown and
described.

DESCRIPTION

FIG. 1 is a perspective view of the food chopper showing my
new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of a portion indicated with
numeric 9 in FIG. 2;

FIG. 10 is a perspective view of the another part of food
chopper showing my new design;

FIG. 11 is a perspective view of FIG. 10 from another angle;

FIG. 12 is a front elevational view of FIG. 10;

FIG. 13 is a rear elevational view of FIG. 10;

FIG. 14 is a left side elevational view of FIG. 10;

FIG. 15 is a right side elevational view of FIG. 10;

FIG. 16 is a top plan view of FIG. 10;

FIG. 17 is a bottom plan view of FIG. 10;

FIG. 18 is an assembled perspective view of FIGS. 1 and 10;

FIG. 19 is a perspective view of FIG. 18 from another angle;
and,

FIG. 20 is a perspective view of FIG. 18 when it is being
used.

FIGS. 1-9, which show the upper portion of the food
chopper, and FIGS. 10-17, which show the lower portion of
the food chopper, are shown separately for clarity of illus-
tration. FIGS. 18-20 show the food chopper in its assembled
state.

1 Claim, 20 Drawing Sheets
